(57) **CLAIM**

The ornamental design for a mobile terminal, as shown and described.

DESCRIPTION

FIG. 1 is a front perspective view of a mobile terminal, showing my design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is a rear perspective view thereof; and,

FIG. 9 is an enlarged view of the encircled portion 9 in FIG. 1.

The broken lines illustrating portions of the mobile terminal form no part of the claimed design. The dot-dash broken lines encircling a portion of the mobile terminal are illustrating a boundary of an enlarged view and form no part of the claimed design.
